(57) **CLAIM**

The ornamental design for a device housing, as shown and described.

DESCRIPTION

FIG. 1 is a top perspective view of a device housing of the present invention showing our new design;

FIG. 2 is a bottom perspective view thereof;

FIG. 3 is another top perspective view thereof;

FIG. 4 is another bottom perspective view thereof;

FIG. 5 is a top plan view thereof;

FIG. 6 is a bottom plan view thereof;

FIG. 7 is a front end view thereof;

FIG. 8 is a rear end view thereof;

FIG. 9 is a right side view thereof; and,

FIG. 10 is a left side view thereof.

The broken lines shown in the drawings depict portions of the device housing that form no part of the claimed design.

1 Claim, 8 Drawing Sheets
